UNITED STATES PATENT OFFICE.

ANDREW C. HUMPHREYS, OF URBANA, OHIO.

DEVICE FOR PURIFYING LIQUIDS.

SPECIFICATION forming part of Letters Patent No. 232,822, dated October 5, 1880.

Application filed April 10, 1880. (No model.)

To all whom it may concern:

Be it known that I, ANDREW C. HUMPHREYS, of the city of Urbana, in the county of Champaign and State of Ohio, have invented certain 5 new and useful Improvements in Devices for Purifying Liquids, of which the following is a specification.

The object of my invention is the provision of cheap, convenient, and effectual means 10 whereby liquids can be cleaned from sediment and other impurities held therein by suspension.

The nature of my invention will be fully apparent from the following description.

Among the various instances in which my 15 improvements can be applied is that known as the "driven well," and inasmuch as the mode in which my invention operates with a driven well is a good illustration of how it operates in every instance, I have shown my invention 20 as applied to and operating in connection with such a well.

In the accompanying drawings, making a part of this specification, Figure 1 is a view, in perspective, of the exterior of a device embodying my invention. Fig. 2 shows a vertical central section of the same, taken through outlet 25 and pipe B of Fig. 1, and also showing, by dotted lines, a pump attached to the upper end thereof.

30 A indicates the entire device, and B represents the inlet-pipe through which the liquid to be cleansed enters the receiver C. For the sake of compactness this inlet-pipe B is so curved near and at its inlet-orifice that the latter shall 35 be directly below the bottom of the receiver and shall terminate in an end to which the vertical pipe or conduit of a driven well may at pleasure be conveniently attached in any of the customary and well-known modes of connecting the ends of pipes or tubing. In cases 40 where the pipe or conduit supplying the liquid is horizontal, or in a direction other than vertical, the direction of the end of pipe B must be changed to meet and make a proper connection with the supply-pipe.

45 The pipe B discharges into the receiver C at the upper part of the latter, as shown, so as to allow room in the receiver below the point of its discharge into the latter for sediment, &c., 50 to collect without clogging its discharge-aper-

ture E, and to enable the pipe B to discharge its contents into the receiver without stirring up the sediment collecting at the bottom of said receiver.

The pipe B is further provided, near its point 55 of discharge into the receiver, with an elbow, F, and, the direction of the latter being nearly horizontal, causes the discharge of liquid from pipe B into the receiver to be in a horizontal direction, thereby the better enabling the weight 60 of the impurities, sediment, &c., in the liquid to assist in causing the impurities to settle to the bottom of the receiver. In other words, the impulsion imparted to said impurities by the current of liquid through the pipe B does 65 not operate to force this sediment, &c., up into the outlet-pipe of the receiver, but allows the force of gravity to freely act in drawing them to the bottom of the receiver.

For the purposes of more effectually preventing any of the impurities circulating in the receiver from being carried up into the outlet-orifice H of the receiver, a wire screen, I, is placed across the upper portion of the receiver, and this screen catches the impurities, &c., and prevents them passing through into said outlet-orifice H, and when the liquid is quite full of impurities a second screen, J, is placed in the receiver and at a short distance from and in front of the discharge-orifice E of pipe B, so as to check the passage of the impurities toward the outlet H, and for the better enabling the screen J to deflect the upward course of the impurities, and to allow the latter an opportunity to fall without adhering to the screen J, the latter is inclined from a point at the side of the receiver some little distance above the discharge-orifice E of pipe B, in a downward direction, diagonal to the length of the receiver and toward the center of the latter. (See Fig. 2.)

For convenience of construction and of attachment of the screens I and J, the receiver is constructed in two parts—viz., a main portion, A, and a cap, L, arranged to be connected 95 in any suitable manner. One mode is that shown—viz., the main portion K and cap L are provided with outwardly-extending flanges connected together by bolts N. Between the faces of the cap L and the main portion K the 100

edges of the screens are located, and the screens themselves are thus firmly held in position; but any other desirable mode of attaching the screens to the receiver may be employed. The 5 upper end of the cap L, containing the orifice H, is to be formed so as to be suitably secured in any of the well-known methods to the outlet-tube or conduit above it. In the present instance the lower end of pump P (shown in 10 dotted lines in Fig. 2) is screwed into the upper end of cap L.

The sand or other sediment collecting in the bottom of the receiver must, at suitable intervals, be removed, and for this purpose there is 15 provided the sediment-outlet Q, located substantially as shown, so as to enable the sediment collecting at the bottom of the receiver to be most conveniently discharged. This outlet Q is closed by a suitable device—in the 20 present instance by a screw-plug, R, screwed into the receiver, so as to close the said orifice. The screw-plug R is provided with a square head, so that by the application of a wrench it may be screwed into or out of the orifice Q.

25 To facilitate the removal of the sediment, &c., collected at the bottom of the receiver C, the bottom of the latter is preferably made to slant from the side of the receiver opposite to where the orifice Q is located downwardly to 30 the said orifice. The weight of the sediment, &c., will thus aid in its removal. The pipe or conduit B is made or cast in one piece with the receiver or portion K thereof.

When my invention is employed to separate sand, &c., from the water or oil of a driven well the device A is usually placed just 35 below the pump and above the tubing of the well, and is connected to both pump and tubing.

40 The mode in which my invention operates is as follows: The liquid enters the pipe B at D, and is discharged at E. Where device Fig. 2 is employed the liquid strikes against screen J, which collects the impurities circulating in the liquid, and allows the same to fall to the bottom of the receiver. The liquid passes on, mostly through the screen J and up to screen I, which also stops such impurities which have got from under screen J and 45 been carried up to screen I, and prevents their ingress into orifice H and the pump P. The liquid is thereby delivered free of sediment, and the valves of the pump are prevented from being cut, worn, or clogged by sediment or 50 other impurities.

55 My invention is of great value in clearing the running waters of springs. Where, however, the flow of liquid through the receiver is intermittent, as is usually the case when a 60 pump is employed, the sediment, &c., circulating in the water has a better opportunity of settling to the bottom.

When the receiver has become quite full of sediment, &c., the plug R is withdrawn and 65 the sediment removed through orifice Q. The

liquid in the receiver, in its endeavor to pass out of said orifice, will aid in removing said sediment, &c., and where the receiver is provided with a slanting bottom, W, gravity will aid in removing the said sediment.

70 Where the supply of liquid to the receiver is continuous, as in the case of a spring, the pressure and flow of liquid to the receiver will very rapidly carry the sediment, &c., through the orifice Q.

75 What I claim as new, and desire to secure by Letters Patent, is—

1. The receiver provided with sloping bottom W, sediment-outlet R located in the side of the receiver and at the lowest point of said sloping bottom, and also provided with outlet-orifice H, located in the top of said receiver, in combination with the inlet-conduit D B, beginning at the bottom of the receiver, substantially as shown, and extending upward 80 along the outside of said receiver and entering the latter near its top through orifice E, the receiver and the conduit D B being made in one piece, substantially as and for the purposes specified.

2. The combination of the cap L, provided with outlet H, and portion K, provided with sloping bottom W, sediment-outlet R located at the side of the receiver, and at the lowest point of the said sloping bottom, and inlet-conduit D B, beginning at the center of the bottom of said receiver and extending upward along the side of the latter and entering the latter near its top through orifice E, portion K of the receiver and said conduit D B being made in 90 one piece, substantially as and for the purposes specified.

3. The combination of cap L, provided at its top with outlet H, and portion K, having sediment-outlet R, and inlet-conduit D B, beginning at the center of the bottom of said receiver, and extending upwardly along the side of the latter and entering the latter near its top through the orifice E, portion K of the receiver and said conduit being made in one 105 piece, substantially as and for the purposes specified.

4. The combination of cap L, provided at its top with outlet H, and screen I, and portion K, having sediment-outlet R, and inlet-conduit D B, beginning at the center of the bottom of said receiver, and extending upwardly along the side of the latter and entering the latter near its top through the orifice E, portion K of the receiver and said conduit being made in one 115 piece, substantially as and for the purposes specified.

5. The combination of cap L, provided at its top with outlet H, and portion K, having sediment-outlet R and screen J, and inlet-conduit D B, beginning at the center of the bottom of said receiver, and extending upwardly along the side of the latter and entering the latter near its top through the orifice E, portion K of the receiver and said conduit being 125

made in one piece, substantially as and for the purposes specified.

6. The combination of cap L, provided at its top with outlet H, and screen I, and portion K, having sediment-outlet R, and screen J, and inlet-conduit D B, beginning at the center of the bottom of said receiver, and extending upwardly along the side of the latter and

entering the latter near its top through the orifice E, portion K of the receiver and said 10 conduit being made in one piece, substantially as and for the purposes specified.

ANDREW C. HUMPHREYS.
